UNITED STATES PATENT OFFICE.

WILLIAM J. SCHIEFFELIN, OF NEW YORK, N. Y.

SURGICAL AMPUL.

1,263,940.

Specification of Letters Patent.

Patented Apr. 23, 1918.

Application filed September 27, 1917. Serial No. 193,555.

To all whom it may concern:

Be it known that I, WILLIAM J. SCHIEFFELIN, a citizen of the United States, and a resident of the city of New York, borough 5 of Manhattan, in the county and State of New York, have invented a new and Improved Surgical Ampul, of which the following is a full, clear, and exact description.

This invention relates to an ampul or capsule container designed to hold a tincture of iodin or any other antiseptic fluid, and the invention has to deal more particularly with the construction of the container whereby it is especially adapted for army use, al- 15 though it is not necessarily limited thereto.

Heretofore it has been proposed to make the ampul or container of glass which is broken open at one end when it is desired to pour out the contents on a wound, but 20 this is dangerous, as sometimes splinters or fragments of glass will be introduced into the wound, and also a puncture or wound may be made in the fingers when breaking the glass ampul.

25 The object of the present invention is to provide a non-breakable, easily-portable and instantly-available emergency supply of iodin tincture or other antiseptic fluid by making the container of paraffin wax or ozoce- 30 rite, which can be readily opened by the finger-nail, or by the teeth when one hand is disabled and the other hand is using the ampul, without danger from fragments of the paraffin container if they enter the wound, it 35 being recognized that paraffin is not deleterious.

40 Preferably the wax container with the antiseptic therein is arranged in a suitable box to prevent injury, and the container is of such size as to contain sufficient tincture of iodin for one application. The protective box or casing in which the ampul is contained is preferably separable in the middle so that when the cover is removed a portion 45 of the ampul will project and the tip can be opened for pouring the contents out without the necessity of withdrawing the ampul from the body of the box.

45 For a more complete understanding of the invention reference is to be had to the following description and claims taken in connection with the accompanying drawing, in which similar characters of reference indi-

cate corresponding parts in all the views, and in which—

55 Figure 1 is a perspective view of the ampul.

Fig. 2 is a longitudinal section thereof; and

Fig. 3 is a longitudinal section showing 60 the ampul in the protective case or box.

Referring to the drawing, the ampul comprises a body 1 made of suitable material, such as paraffin wax or ozocerite, the body being tubular and having tapering closed 65 ends 2, whereby a hermetically sealed container or capsule is obtained for holding a suitable quantity of tincture of iodin or other antiseptic fluid 3. In other words, the ampul is a container having flexible, pliable 70 walls which are not easily broken and which can be readily severed by the finger-nails or by the teeth when the ampul is to be opened to pour out the contents.

The ampul is preferably protected in a 75 casing, such as a turned wood box comprising a body 4 and cap 5, the depth of the body being such that approximately half of the ampul extends out of the same when the cap is removed. This is advantageous, be- 80 cause the ampul is always available, even in case it should stick in the case 4, due to the heat causing the paraffin to soften and adhere to the walls of the case or body 4. When thus incased the ampul is especially 85 adapted for a soldier's kit, whereby an anti-septic will be always available for a wound.

From the foregoing description taken in connection with the accompanying drawing, the advantages of the construction and 90 method of operation will be readily understood by those skilled in the art to which the invention appertains, and while I have described the principle of operation, together with the article which I now consider 95 to be the best embodiment thereof, I desire to have it understood that the article shown is merely illustrative and that such changes may be made when desired as fall within the scope of the appended claims.

Having thus described my invention, I claim as new and desire to secure by Letters Patent:

1. A first-aid ampul comprising a container of waxy material having a melting 105 point about one hundred and thirty degrees

Fahrenheit, the container being pointed at its end and holding an alcoholic solution of iodin.

2. A first-aid ampul comprising a container of paraffin pointed at its end and holding an alcoholic solution of iodin.

3. A first-aid ampul comprising a container of paraffin and having both ends pointed, and a holder composed of two parts in either of which the ampul may be held 10 with a pointed end projecting.

WILLIAM J. SCHIEFFELIN.
